(57) **CLAIM**

The ornamental design for a foam applicator for applying a fluid, as shown and described.

DESCRIPTION

FIG. 1 is an exploded top perspective view of a foam applicator for applying a fluid.

FIG. 2 is top perspective view of the foam applicator for applying a fluid in a closed position.

FIG. 3 is a front view of the foam applicator for applying a fluid in a closed position, the rear view being a mirror image.

FIG. 4 is a right side view of FIG. 2.

FIG. 5 is a left side view of FIG. 2.

FIG. 6 is a top view of FIG. 2.

FIG. 7 is a bottom view of FIG. 2.

FIG. 8 is a bottom perspective view of FIG. 2.

FIG. 9 is another bottom perspective view FIG. 2.

FIG. 10 is a top perspective view of the foam applicator for applying a fluid shown without the cap for convenience of illustration.

FIG. 11 is a front view of FIG. 10, the rear view being a mirror image.

FIG. 12 is a right side view of FIG. 10.

FIG. 13 is a left side view of FIG. 10.

FIG. 14 is a top view of FIG. 10.

FIG. 15 is a bottom view of FIG. 10.

FIG. 16 is a bottom perspective view of FIG. 10.

FIG. 17 is another bottom perspective view of FIG. 10.

FIG. 18 is a top perspective view of the cap portion of the foam applicator for applying a fluid shown separately for convenience of illustration.

FIG. 19 is a side view of the cap, the opposite side, front and rear views being mirror images.

FIG. 20 is a bottom perspective view of the cap; and,

FIG. 21 is a bottom view of the cap.
